(57) **CLAIM**

The ornamental design for an animal house as shown and described.

DESCRIPTION

FIG. 1 is a top, front, left perspective view of an animal house of my new design;

FIG. 2 is a bottom, front, left perspective view thereof;

FIG. 3 is a front elevation view thereof;

FIG. 4 is a rear elevation view thereof;

FIG. 5 is a right-side elevation view thereof;

FIG. 6 is left-side elevation view thereof;

FIG. 7 is a top plan view thereof; and,

FIG. 8 is a bottom plan view thereof.

The broken lines show features of the animal house that form no part of the claimed design.
